United States Patent Office.

FREDERICK STAMLER, OF HAMBURG, NEW YORK.

Letters Patent No. 99,967, dated February 15, 1870.

IMPROVEMENT IN TREADLES FOR SEWING-MACHINES.

The Schedule referred to in these Letters Patent and making part of the same.

I, FREDERICK STAMLER, of Hamburg, in the county of Erie, and State of New York, have invented certain Improvements in the "Treadles for Sewing and other Machines," of which the following is a specification.

The nature of my invention consists in providing the treadle for sewing-machines or other light machinery with a step or foot-board, so arranged that the foot in working the treadle may not be obliged to oscillate, but to rise up and move down in a near perpendicular line. This I accomplish by providing an axis for the step or foot separately from that of the main axis.

I refer to the drawing, which illustrates the nature of my invention more fully, and which makes part of this specification.

Figure 1 represents a sewing-machine frame and table provided with a treadle, improved as aforesaid, in a perspective view.

Figure 2 is a cut through the two axes and foot-board of the treadle.

Letter A is the main shaft or axis of treadle.

To the same is secured an adjustable lever, B, which has connection with the fly-wheel C, by means of connecting-rod D. Said lever is adjustable for the purpose of so accommodating the foot-board to the foot as to give it the desired travel.

E is the foot-board frame. The same is secured to the shaft A, in which it is adjustable, as plainly seen in fig. 2.

Said frame is provided with two locks, E', in order to serve as bearings for the axis or pivots of foot-board F.

It will be observed that if the foot is set on the foot-board F and the treadle is set in motion, the foot is not compelled to oscillate with the treadle, but will move straight up and down, hence the working of this treadle is done with more ease.

Having thus fully described my invention, What I desire to secure by Letters Patent, is—

Providing a treadle with a foot-board or foot-boards, arranged so as to have an independent axis from that of the main shaft A, substantially as shown and set forth.

Also, the combination of main shaft A, adjustable lever B, adjustable frame E, and hinged foot-board F, substantially as specified.

FREDERICK STAMLER.
